DESIGN FOR A TERMINAL

Louis A. Koch, Jr., Louisville, Ky.

Application July 7, 1932. Serial No. 44,273

Term of patent 14 years

To all whom it may concern:

Be it known that I, LOUIS A. KOCH, JR., a citizen of the United States, residing at Louisville, in the county of Jefferson and State of Kentucky, have invented a new, original, and ornamental Design for Terminals, of which the following is a specification, reference being had to the accompanying drawing, forming part thereof.

In the drawing

Fig. 1 is a plan view showing my new design;
Fig. 2 is a side elevation and
Fig. 3 is a longitudinal sectional view thereof.

I claim:

The ornamental design for a terminal, as shown.

LOUIS A. KOCH, JR.
